UNITED STATES PATENT OFFICE.

RALPH THOMPSON, OF DETROIT, MICHIGAN, ASSIGNOR OF ONE-HALF TO
HUGO A. WINEMANN, OF SAME PLACE.

COMBINED PENCIL AND SCISSORS HOLDER.

SPECIFICATION forming part of Letters Patent No. 328,866, dated October 20, 1885.

Application filed April 29, 1885. Serial No. 163,840. (No model.)

To all whom it may concern:

Be it known that I, RALPH THOMPSON, of Detroit, in the county of Wayne and State of Michigan, have invented new and useful Improvements in a Combined Pencil and Scissors Holder; and I do hereby declare that the following is a full, clear, and exact description thereof, reference being had to the accompanying drawings, which form a part of this specification.

This invention relates to certain new and novel improvements in devices designed to be pinned or otherwise secured to wearing-apparel for the purpose of holding a pencil and scissors. This device will be found especially useful by clerks in dry-goods establishments, where the pencil and scissors are frequently used, and the clerk, if a man, carries a pencil and scissors in his pocket, from which they are liable to drop out and be lost, while, if a lady, the pencil is generally stuck in her hair and the scissors hung from a long tape attached to the waist.

It is the object of this invention to provide a device that can readily be attached to the dress or coat and into which the pencil and scissors can be inserted and held against accidental displacement.

To this end the invention consists in the peculiar construction and arrangement of the holder, all as more fully hereinafter set forth.

Figure 1 is an elevation of my improved device, showing a pencil and scissors inserted in their respective holders. Fig. 2 is a cross section on line $x-x$, Fig. 1. Fig. 3 is a plan of the plate from which the device is made.

In the accompanying drawings, which form a part of this specification, A represents a plate, of suitable sheet metal, stamped out in

substantially the form shown. One end (the 40 right-hand end in the drawings) is bent over and formed into a socket, B, for the reception of the scissors, while the opposite end is bent circular, forming a receptacle to receive a pencil, and the overlapping ends are secured 45 together and to the body of the plate A by a suitable rivet, a. That portion of the plate that forms the front walls of the pencil and scissor-receptacles is provided with downwardly-projecting arms b, the ends of which 50 are bent inwardly or toward the body of the plate so as to contract the openings at the bottoms of the receptacles and prevent the pencil or scissors from falling through. A suitable safety pin or pins, c, should be secured to the back of the plate, by means of which the device can readily be attached to the coat or dress.

What I claim as my invention is—

1. A combined pencil and scissors holder 60 formed from a single blank of metal bent to bring both ends into contact with the body, and both ends secured to the body by a single rivet, as set forth.

2. A combined pencil and scissors holder 65 comprising a single piece of metal cut to provide spring-fingers bent to throw the ends past each other and both ends secured to the body by a single rivet, as set forth.

3. The pencil and scissors holder described, 70 consisting of the single piece of metal cut to form a curved blank with spring-fingers b, and bent and secured by a single rivet to form tapering receptacles, as set forth.

RALPH THOMPSON.
